UNITED STATES PATENT OFFICE.

LAURENCE BEDDOME TURNER, OF CAMBRIDGE, ENGLAND.

WIRELESS-TELEGRAPH RECEIVER.

Application filed February 9, 1921. Serial No. 443,636.

To all whom it may concern:

Be it known that I, LAURENCE BEDDOME TURNER, a subject of the King of Great Britain, and residing at Kings College, Cambridge, England, have invented certain new and useful Improvements in Wireless-Telegraph Receivers, of which the following is a specification.

In high-speed signalling by wireless telegraphy with long waves and with receiving circuits of small damping, limitation of speed is imposed by the slowness with which the oscillation produced in the receiving circuit during a dot or dash of the signalling code dies away during the subsequent space of the signalling code. The rate of dying away is increased if the damping is increased; but the amplitude reached is then decreased, which implies a decrease in the 20 sensitiveness of the receiver.

The present invention consists in the provision of means whereby the received signal (dot or dash, in the Morse code), upon reaching an amplitude competent to operate the receiving instrument, introduces additional damping into the receiving circuit; which additional damping is maintained as long as the incoming signal is maintained but automatically disappears, or substantially disappears during the next spacing period. The automatic increasing of the damping is hereinafter referred to as "curbing"; and curbing is said to begin when the 30 additional damping is first introduced, and to end when it is removed. The curbing is preferably maintained throughout as large a proportion of the spacing period as possible. Under these conditions, the decrement of the uncurbed receiving circuit may be made small, thus favouring the growth of the oscillation in the receiving circuit up to its operative amplitude; the curbing thereupon effected imposes a restriction on the further growth of amplitude; and, if the 40 curbing is maintained for a time after the cessation of the incoming signal, the rate at which the amplitude dies away towards zero is greater than that corresponding to the decrement of the uncurbed circuit.

Curbing may be effected in all or any of the receiving circuits, including the antenna circuit itself; but the arrangement preferred is one in which the antenna is relatively highly damped, and has coupled to it a circuit of specially low decrement to which the curbing is applied. The low decrement

of the uncurbed receiving circuit may be arrived at in any known way, with or without the aid of retroactive thermionic triode circuits associated with the receiving circuit 60 for the purpose of reducing its decrement in the well known manner.

One way of curbing the oscillatory receiving circuit is to cause the received oscillation to deflect the tongue of a relay which, in the spacing position, short-circuits a resistance comprised in the oscillatory circuit, but ceases to do so when deflected into the marking position. The relay may be made somewhat sluggish of return to the spacing position, so as to prolong the duration of the marking contact, and to maintain the curbing during part of the spacing period; and mechanical or electrical devices may be used to maintain the curbing for a while 70 after the tongue of the relay has returned to the spacing position.

Alternatively, the tongue of the relay may control the grid or anode potential, and thereby the anode-anode slope conductance, 80 of a thermionic triode connected to the receiving circuit in such a way as to produce in it more or less damping according to the value of the said anode-anode slope conductance. If the relay controls the anode potential of the thermionic tube, the grid may be dispensed with, and a diode or Fleming valve may be substituted for the triode.

The relay may be of any pattern, and may be actuated by the received oscillation in any 90 way, with or without intermediate amplifiers.

The invention is more particularly described by reference to the following figures, 95 which illustrate particular methods of putting it into effect. Figure 1 shows an arrangement in which resistance is switched into and out of the receiving oscillatory circuit by a relay directly; and Figure 2 shows one method of effecting the curbing 100 by an intermediary thermionic tube under control of the relay.

In both the figures, L is an inductance and C is a condenser comprised in the receiving oscillatory circuit which is to be curbed. An oscillation is built up in LC by the incoming signal, and is arranged to actuate any form of detecting or recording instrument associated with it in the usual way. 1 is a relay actuated by the oscillation in LC through a 110 rectifier such as crystal or thermionic rectifier 2, and is shunted by a condenser 3.

and a resistance 4. The resistance 4 may, however, sometimes be omitted. The deflection of 1 from the spacing position S to the marking position M effects the introduction of additional damping into the oscillatory circuit. Relay 1 may actuate the recording instrument not shown. According to the theory well understood, in order that a given incoming signal may build up a large amplitude of oscillation in LC during the marking period of the incoming signal, the decrement of LC should be small; but in order that the oscillation may die down sufficiently rapidly when the incoming signal ceases, the quantity $(R \cdot T)/L$ must be kept sufficiently large, where R is the total effective resistance of the oscillatory circuit, and T is the duration of the spacing period at the speed of signalling in use.

In Figure 1, 5 is an additional resistance inserted in the LC circuit, and is wholly or partially short-circuited when the relay is at S, but is not short-circuited when the relay is at M. Until the oscillation in LC has been built up sufficiently to actuate 1, the decrement is small; but when 1 is deflected curbing begins. The value of the resistance short-circuited by 1 is preferably made just great enough to prevent any substantial further growth of the oscillation after curbing begins. Curbing continues until 1 returns from M to S, which event may be more or less delayed after the termination of the incoming signal by adjusting the sluggishness of the relay due to 4, as well as by the usual mechanical adjustments of the relay.

In Figure 2, 6 is a thermionic triode, with filament 7, grid 8 and anode 9. 10 is the filament battery, and 11 the anode battery. The whole or part of L is inserted in the anode circuit 9, L, 11, 7. 12 is a battery tending to maintain the grid at a potential $(-E^{12})$ with respect to the filament. 13 is a high resistance interposed between 12 and 7 and shunted by a condenser 14. 15 is a battery of electromotive force E^{15} , and is so connected, through the tongue and the M contact of the relay, across 13 and 14 as to raise the grid potential to the value $(E^{15} - E^{12})$ when the relay is deflected to M. When the relay returns to S, the potential of 8 falls gradually at a rate determined by the time-constant of 13, 14, and would finally again reach $(-E^{12})$.

It is well known that when the grid potential is sufficiently low, the anode-anode slope conductance is extremely low, in which condition 6 might introduce negligible damping into the oscillatory circuit; and that when the grid potential is raised to a suitable value, the anode-anode slope conductance rises to some relatively very high value, in which condition 6 introduces more or less damping into the oscillatory circuit as more

or less of L is included in the anode circuit. The anode-anode slope conductance is approximately constant over a considerable range of grid potential, and $(E^{15} - E^{12})$ is preferably made to lie near the upper end of this range; while E^{12} is preferably given such a large value as to make the anode-anode slope conductance sensibly zero before curbing occurs. When the relay is at M, the oscillatory circuit is curbed by 6, and remains curbed after the relay leaves M until the grid potential has fallen to a considerably lower value. The rate of fall, and therefore the duration of curbing after the relay leaves M, is controlled by adjusting the product of the resistance of 13 and the capacity of 14. The adjustment is preferably made so as to cause curbing to continue as long as possible during the spacing period of the incoming signal.

The amount of additional damping introduced may be chosen to suit special conditions; but with undamped incoming signals it will generally be convenient to make the decrement of the oscillatory circuit during curbing as great as possible, namely, of the value which would give an amplitude of oscillation under a continued signal equal to the operative amplitude. During curbing the current then remains constant at the operative value until the incoming signal ceases, whereupon it falls with the greatest possible rapidity.

Having thus described my invention what I claim as new and desire to secure by Letters Patent is:—

1. Apparatus for use in wireless telegraphy, comprising an oscillatory receiving circuit of relatively low decrement, a connection including a relay joined to the oscillatory circuit and means operated by said relay for increasing automatically the decrement of the oscillatory circuit when the amplitude of the current therein reaches the operative value.

2. Apparatus for use in wireless telegraphy, comprising an oscillatory receiving circuit of relatively low decrement, a connection including a rectifier and a relay joined to the oscillatory circuit and means operated by said relay for increasing automatically the decrement of the oscillatory circuit when the amplitude of the current therein reaches the operative value.

3. Apparatus for use in wireless telegraphy, comprising an oscillatory receiving circuit of relatively low decrement, a connection including a relay joined to the oscillatory circuit and means operated by said relay for increasing automatically the decrement of the oscillatory circuit when the amplitude thereof reaches the operative value, said means being adapted to retain the increased decrement during the spacing period following the signal.

4. Apparatus for use in wireless telegraphy comprising an oscillatory receiving circuit of relatively low decrement, a connection including a relay, joined to the oscillatory circuit, and a thermionic tube with connections coupling it to the oscillatory circuit and means for controlling the potential of the grid of the thermionic tube by the relay whereby additional decrement is applied to the oscillatory circuit. 30
5. Apparatus for use in wireless telegraphy comprising an oscillatory receiving circuit, a connection including a relay joined to the oscillatory circuit, a condenser and a resistance, shunting the relay, and means controlled by the relay for applying additional decrement to the oscillatory receiving circuit. 35
- 10 6. Apparatus for use in wireless telegraphy comprising an oscillatory receiving circuit including an inductance and a condenser, a connection including a relay, joined across the condenser to the oscillatory receiving circuit, a thermionic tube, means connecting the anode circuit of said thermionic tube to the inductance, means for controlling the potential of the grid of said thermionic tube by the relay, said means in- 40
- 15 cluding a battery adapted in one position of the relay to increase the grid potential and a high resistance and condenser in the grid-filament circuit of the thermionic valve, said resistance and condenser being in parallel with said battery when the battery circuit is closed by the relay. 45
- 20 7. Receiving apparatus for wireless telegraphy comprising an oscillatory receiving circuit of relatively low decrement and means responsive to the magnitude of currents in said receiving circuit for materially increasing automatically the decrement of said oscillatory circuit. 50
- 25 8. Apparatus for use in wireless telegraphy comprising an oscillatory receiving circuit of relatively low decrement, a relay, connections between said receiving circuit and said relay whereby said relay receives a current the magnitude of which increases with the magnitude of the current in said receiving circuit and means operated by said relay for increasing automatically the decrement of the oscillatory circuit when the amplitude of the current therein attains a predetermined value. 55
